UNITED STATES PATENT OFFICE.

ALONZO E. RHODES, OF HOPEDALE, MASSACHUSETTS, ASSIGNOR TO
DRAPER COMPANY, OF HOPEDALE, MASSACHUSETTS, A CORPORA-
TION OF MAINE.

SLASHER-COMB.

No. 818,560.

Specification of Letters Patent.

Patented April 24, 1906.

Application filed August 7, 1905. Serial No. 273,006.

To all whom it may concern:

Be it known that I, ALONZO E. RHODES, a citizen of the United States, and a resident of Hopedale, county of Worcester, State of Massachusetts, have invented an Improvement in Slasher-Combs, of which the following description, in connection with the accompanying drawings, is a specification, like characters on the drawings representing like parts. This invention has for its object the production of a novel comb intended more particularly for use in connection with slashers, whereby an increased number of warp-guiding dents are provided without increasing the number of shanks or feet which coöperate with the means for sustaining and governing the lateral position of the dents and also whereby increased lateral support is provided for the warps to maintain them properly spread as they pass to the beam.

The novel features of my invention will be fully described in the subjoined specification and particularly pointed out in the following claims.

Figure 1 is a front elevation, centrally broken out, of a comb embodying one form of my present invention. Fig. 2 is an enlarged transverse section thereof on the line 2 2, Fig. 1, looking toward the right; and Fig. 3 is a horizontal section through the dents on the line 3 3, Fig. 2, showing how the capacity of the comb can be increased for opening out the warp.

I have illustrated my present invention in connection with a slasher-comb case of well-known construction, inasmuch as my invention is particularly adapted for use in connection therewith.

Referring to Figs. 1 and 2, the base 1 of the case, having a longitudinal recess 2 (see Fig. 2) to receive the feet or shanks of the warp-guides, the rotatable right and left hand screw-threaded adjusting shaft or rod 3 mounted in usual manner, the sleeves or nuts 4, controlled by the rod 3, (only one of the sleeves being herein shown,) the coiled springs 5, arranged in pairs and attached at their ends to the nuts or sleeves, the longitudinally-extended guides 5, passed through the springs, and the longitudinal slot 6 in the top of the comb-case, may be and are all substantially of well-known construction and operate in usual manner.

The warp guides or dents are usually made

as thin flat metal strips having their lower ends or shanks extended through the coils of the springs, their upright upper ends projecting through the cover of the case and constituting the dents, one for each shank.

It is sometimes desirable to provide an increased number of dents in order to effect a better and more complete separation of the warps, and also in other cases to increase the resistance to the lateral pull of the warps as they pass through the dents, and by means of my present invention I am enabled to attain both objects without increasing the number of or enlarging the guide-shanks which coöperate with the springs.

Referring to Fig. 2, I have shown one of the warp-guides in enlarged side elevation and consisting of an elongated shank 15, having its upper end bifurcated or branched to present two upright dents 16 17, the former being shown as a prolongation of the shank and in the same plane. The dent 17 is separated from dent 16 in a fore-and-aft direction, leaving an opening 18, and it is also laterally offset (see Fig. 3) by means of the bent neck 19, connecting the dent 17 and the shank. The warp-guides are made of flat sheet metal of proper thickness stamped or struck out in any suitable manner, the bending of the neck 19 bringing the two dents on each shank into parallel but laterally-separated planes, and when the device is in use two parallel rows of dents will be presented, as shown in Fig. 3, the dents in one row being located opposite the spaces between adjacent dents in the other row.

Notwithstanding the fact that the number of dents has been doubled by the construction described it will be manifest that the number of parts of the warp-guides coöperating with the springs has not been increased. Referring to Fig. 3, it will be seen that the warps *w* are led through the clearance-spaces 18 and that other warps *w'* are led between the pairs of dents, giving a more complete separation or division of the warps, which is at times very desirable. The double-dent arrangement is also very efficient in maintaining the yarn spread laterally in the slasher, the dents having sufficient strength to properly resist the strain exerted by the warps.

My invention is not restricted to the precise construction and arrangement shown

and described herein, as the same may be modified in various particulars by those skilled in the art without departing from the spirit and scope of my invention.

5 Having fully described my invention, what I claim as new, and desire to secure by Letters Patent, is—

1. In a comb of the class described, an elongated base, warp-guides each comprising a shank having a plurality of upright and laterally-offset dents, and means to sustain and laterally position the warp-guides.

2. In a comb of the class described, a series of warp-guides each comprising a shank having two upright, separated flat dents laterally offset from each other and in parallelism, and means to sustain and laterally position said warp-guides.

3. In a comb of the class described, a series of warp-guides each comprising a flat shank bifurcated at its upper end to present two flat dents having their inner edges separated, said dents being laterally offset and one of them forming a continuation of the shank.

25 4. As a new article of manufacture, a metallic warp-guide for combs, comprising a shank having two elongated, separated dents thereon laterally offset from each other.

30 5. As a new article of manufacture, a metallic warp-guide for combs, comprising a flat shank bifurcated at its upper end to present

two flat, separated dents laterally offset from each other and in parallelism.

6. As a new article of manufacture, a metallic warp-guide for combs comprising a flat shank bifurcated at its upper end to present two flat, separated dents laterally offset from each other and in parallelism, one of the dents forming a prolongation of the shank and lying in the same plane therewith.

7. In a comb of the class described, an elongated base, longitudinally - extended coiled springs arranged in pairs and adapted to sustain and laterally position the warp-guides, and a series of warp-guides each comprising a shank coöperating with the springs, and two upright flat dents at its upper end, laterally offset from each other and in parallelism, and separated in a fore-and-aft direction.

8. In a comb of the class described, an elongated base, two parallel rows of flat, upright dents laterally offset from each other, a series of shanks with each of which two dents, one in each row, are rigidly connected, and means coöperating with the shanks to support and laterally position the dents.

In testimony whereof I have signed my name to this specification in the presence of two subscribing witnesses.

ALONZO E. RHOADES.
